UNITED STATES PATENT OFFICE.

WALTER H. GAMBLE, OF LOS ANGELES, CALIFORNIA.

RECEPTACLE.

1,132,466.

Specification of Letters Patent. Patented Mar. 16, 1915.

Application filed December 1, 1913. Serial No. 804,122.

To all whom it may concern:

Be it known that I, WALTER H. GAMBLE, a citizen of the United States, residing at Los Angeles, in the county of Los Angeles 5 and State of California, have invented a certain new and useful Improvement in Receptacles, of which the following is a specification.

My invention relates to a receptacle for 10 articles of preferably a long and slim nature, and more especially matches, and has particular reference to an improvement in that class of devices shown in my United States Patent No. 980,625, of January 3, 15 1911, but distinguished therefrom in being itself a container or receptacle instead of an attachment to a container or receptacle.

An object of this invention is to provide 20 a simple, cheap and durable receptacle in which matches, or other articles of a similar nature may be placed and from which they may be readily removed as required, and the invention consists broadly of a 25 scored blank, so foldable that a substantially rectangular receptacle may be formed with a projecting portion at the bottom for leaving exposed and facilitating the removal of the articles from the receptacle. These and other objects are accomplished by the 30 device shown in the accompanying drawing, in which—

Figure 1, is a plan view of the complete blank. Fig. 2 is a perspective view showing the folded receptacle, and Fig. 3, is a vertical section on line 3—3, Fig. 2.

The blank 1, is scored at 2 and 3, to form, when folded at right angles to the back 4, side walls 5 and 6, the wall 5, having continuous therewith a strip 7, scored at 8, to 40 render same easily foldable and form a front for the receptacle. Said strip 7, is provided with a portion 9, scored at 10, and adapted to be lapped over the wall 6. On this portion are tongues 11 and 12, arranged for insertion through slots 13 and 14, respectively, in said wall 6. The walls 5 and 6 are provided with tabs 15 and 16, respectively, foldable on the score 17, at right angles to said walls and occupying substantially the position shown in Fig. 2. Continuous with back 45 4, and bendable at the score 17, to form a bottom for said receptacle, is a portion 18, adapted to overlap the tabs 15 and 16 on the walls 5 and 6, for purposes presently to ap-

pear, and continuous with said bottom portion 18, is a lip 19, foldable on the score 20. This lip 19, when in folded position, as seen in Fig. 2, projects outwardly from the front 7, of the receptacle, and is provided with wings 21 and 22, having spurs 23 and 24, for engagement with the inside of the front 7, to hold the lip in position as shown. The wall 5, is incised to form an ear 25, behind which the spur portion 23, of the wing 21, is inserted, to hold said wing in snug contact 65 with said wall 5. The other spur portion 24, of the wing 22, when in position, lies under the tongue 12, of the portion 9, this provision serving to enable, when desired, a box to be slipped into the receptacle without striking the protruding portion of the spurs. As seen the inwardly folded tabs 15 and 16, lie upon the bottom 18, and the wings 21 and 22 rest upon said tabs, these tabs functioning to perfect the closure of 70 the receptacle at the bottom. The back 4, is provided with an extension 26, at the top, having an aperture 27, whereby to hang the receptacle at any convenient place.

The aforementioned portion 7, forming 80 the front of the receptacle is shorter than the walls 5 and 6 and the back 4, in order to leave, when folded in position, an opening 75 in the front of the receptacle of a height equal to that of the wings.

What I claim, is:—

A receptacle consisting of a single piece of material foldable upon itself to form side walls and a back, one of said walls having a strip arranged to overlap and be fastened 90 by means carried thereby to the other of said side walls, said strip being shorter than said walls and back, a portion continuous with and foldable at right angles to said back to form a bottom, said portion having continuous therewith a lip provided with side wings having locking means for engagement with the strip to hold said lip projected from said strip, and at an angle to said bottom, whereby to leave an opening in the 95 front of said receptacle.

In testimony whereof I have set my hand in the presence of two witnesses.

WALTER H. GAMBLE.
